UNITED STATES PATENT OFFICE

154,226

DESIGN FOR A TUB OR SIMILAR ARTICLE

William E. Ackermann, Wheeling, W. Va., assignor to Wheeling Steel Corporation, Wheeling, W. Va., a corporation of Delaware

Application April 26, 1948, Serial No. 145,959

Term of patent 14 years

(Cl. D49—1)

To all whom it may concern:

Be it known that I, William E. Ackermann, a citizen of the United States of America, residing at Wheeling, West Virginia, have invented a new, original, and ornamental Design for a Tub or Similar Article, of which the following is a specification, reference being had to the accompanying drawings, forming part thereof.

In the drawings

Figure 1 is a perspective view of a tub, showing my new design;

Figure 2 is a top plan view of the tub shown in Figure 1; and

Figure 3 is a side elevational view of the tub shown in Figure 1.

I claim:

The ornamental design for a tub or similar article, substantially as shown.

WILLIAM E. ACKERMANN,
